UNITED STATES PATENT OFFICE.

EDWARD J. F. COLEMAN, OF BARRINGTON, RHODE ISLAND.

SHEET-LEADER BLOCK.

SPECIFICATION forming part of Letters Patent No. 655,851, dated August 14, 1900.

Application filed November 23, 1899. Serial No. 738,004. (No model.)

To all whom it may concern:

Be it known that I, EDWARD J. F. COLEMAN, a citizen of the United States of America, and a resident of Barrington, county of 5 Bristol, and State of Rhode Island, have invented certain new and useful Improvements in Sheet-Leader Blocks, of which the following is a specification.

My invention relates to improvements in 10 "sheet-leader blocks," so called, employed on yachts and other sailing vessels; and it consists, essentially, of a base-plate adapted to be rigidly secured to the deck, a superposed guard-plate swivel-jointed to the base-plate, 15 a link jointed to the guard-plate, and a block or sheave-frame loosely coupled to said link, the axis of the link-pin being at substantially right angles to that of the sheave-pin, all as will be more fully hereinafter set forth and 20 claimed.

In devices of the character forming the subject of my present invention it has been usual heretofore to loosely secure the lower end of the sheave-frame itself to a central eyebolt 25 adapted to be screwed into or pass entirely through a deck-beam, a washer sometimes being interposed between the eye of the bolt and the upper surface of the deck-sheathing. In another case the rigidly-secured base-plate 30 member is provided with upwardly-extending ears carrying a pin on which the link (which in turn sustains the sheave-frame) is mounted to swing. There are objections to the use of sheet-leader blocks just referred to—that 35 is to say, former devices or "fittings" of this class were not adapted to be readily secured to the deck or changed when desired. The sheaves were not capable of sufficient angular movement except in one plane or direction. 40 Therefore the "sheet" or halyard could not lead fair to the sheave at all times. In some of the former devices the sheave-frame when the sheet was slackened sufficiently would drop over upon the deck and mar it. In other 45 cases where it has been attempted to overcome this latter objection the movement of the frame was limited to a comparatively-short arc, thereby when not in use forming an obstruction, since the frame stood in a 50 nearly-vertical position. In such former devices, too, water was liable to work down around the central bolt to the under side of

the deck. By means of my improvement all the foregoing-named objections or disadvantages are overcome. The base-plate has a 55 comparatively-large area and is fastened to the deck by a number of short-screws or other equivalent means, thereby distributing the strain over a greater deck-surface. No water can pass through. The device can be readily 60 secured to or detached from the upper side of the deck. The sheave-frame is capable of swinging in an arc of one hundred and eighty degrees extent and in any direction, its movements when made in different planes being 65 coincident with that of the guard-plate, the rim of the latter being extended to form a rest or support for the frame and keeping it (the frame) from contact with the deck, and, finally, the device is strong yet light and 70 comparatively inexpensive.

In the accompanying sheet of drawings, Figure 1 is a plan view of my improved sheet-leader block, the sheave-frame being dropped to one side, as when not in use; and Fig. 2 is 75 a corresponding combined sectional and side elevation, the sectional portion being taken on line *xx* of Fig. 1.

The following is a detailed description of the device: 80

The base-plate *a* is circular and, as drawn, is adapted to be secured to the deck *d* by means of the three screws *s*. Mounted above and practically enveloping the plate *a* is located the guard-plate *b*, the latter having 85 the downwardly-extending peripheral rim *b'*, reaching nearly to the deck. A headed pivot-pin *c* passes loosely through the center of the base-plate and is riveted or otherwise rigidly secured to the center of the guard-plate, a 90 loose washer *w* being interposed between the adjacent surfaces of the head of the pin and the under side of the base-plate. The upper portion of the guard-plate is provided with a pair of laterally-separated ears *e*, through 95 which a supporting-pin *p* extends, all as clearly shown.

f indicates a well-known form of sheave-frame or block, having the loosely-turning sheave or sheet-leader pulley *p'* mounted 100 therein. The frame is connected or coupled to the transverse pin *p* of the guard-plate by means of the link *l*, the latter swinging on said pin. The link has an eye at its outer

end through which the lower end or tie f' of the frame f freely passes. It will be seen that the axis of the tie portion f' is arranged at substantially right angles to the axis of the pin p , the construction of the several parts being such that the sheave-frame is capable of universal swivel movement.

The device may be readily secured to the deck by first turning the plate b until its hole h registers with a hole in the base-plate a , followed by driving the screw s , and repeating the operating until all the screws are inserted.

It is obvious that the several members constituting the device A may be rendered non-oxidizable in any well-known manner, or they may be made of bronze or other suitable metal.

I claim as my invention and desire to secure by United States Letters Patent—

1. In a sheet-leader block, the combination with the sheave or block carrying frame and a base-plate adapted to be secured to the deck, of an axially-movable guard-plate secured to said base-plate, and a link connect-

ing said pulley or block frame to the central portion of the guard-plate, whereby the pulley-frame is capable of complete axial movement and also adapted to swing through a semicircular arc, substantially as described. 30

2. A sheet-leader block, constructed substantially as shown and described, the same consisting of the base-plate member a adapted to be secured to the deck, the guard-plate b , pivoted to the member a , having a pin p extending transversely through its upper portion, the link l mounted on said pin, and the block or sheave carrying frame f loosely coupled to the link, whereby the leader-pulley is capable of movement in any direction through a semicircular arc, the said member b also serving to keep the frame f from coming in contact with the deck. 40

Signed by me at Providence, Rhode Island, this 22d day of November, A. D. 1899.

EDWARD J. F. COLEMAN.
